US0D1022966S

(12) **United States Design Patent** (10) **Patent No.:** **US D1,022,966 S**
(45) **Date of Patent:** **** Apr. 16, 2024**

(54) **PAIR OF EARPHONES**

(71) Applicant: **Shenzhen Shengling Technology Co., Ltd**, Shenzhen (CN)

(72) Inventor: **Hua Lin**, Shenzhen (CN)

(**) Term: **15 Years**

(21) Appl. No.: **29/912,002**

(22) Filed: **Sep. 12, 2023**

(30) **Foreign Application Priority Data**

Sep. 7, 2023 (CN) 202330579520.2

(51) **LOC (14) Cl.** **14-01**

(52) **U.S. Cl.**

USPC **D14/223**

(58) **Field of Classification Search**

USPC ..... D14/168, 205, 206, 207, 217, 221, 223, D14/225, 372, 496; D24/106, 173, 174 CPC . H04R 1/08; H04R 1/10; H04R 1/105; H04R 1/1016; H04R 1/1033; H04R 1/1066; H04R 5/033; H04R 5/0335; H04R 25/00

See application file for complete search history.

(57) **CLAIM**

The ornamental design for a pair of earphones, as shown and described.

DESCRIPTION

FIG. 1 is a perspective view of a pair of earphones showing my new design;

FIG. 2 is another perspective view thereof;

FIG. 3 is a front elevational view thereof;

FIG. 4 is a rear elevational view thereof;

FIG. 5 is a left side elevational view of each earphone thereof;

FIG. 6 is a right-side elevational view of each earphone thereof;

FIG. 7 is a top plan view thereof;

FIG. 8 is a bottom plan view thereof; and,

FIG. 9 is a perspective view of the pair of earphones where the earphones are received in the charging case.

The dash-dash broken lines in the drawings depict portions of the pair of earphones that form no part of the claimed design.

The broken lines showing a case in FIG. 9 are for the purpose of illustrating environment and form no part of the claimed design.

1 Claim, 9 Drawing Sheets
